PUPPET

Freda Lingstrom, Westerham, England

Application May 25, 1954, Serial No. 30,652

Term of patent 14 years

(Cl. D34—4)

To all whom it may concern:

Be it known that I, Freda Lingstrom, a subject of Her Britannic Majesty, residing at Chartwell Cottage, Westerham, in the county of Kent, of Great Britain, have invented a new, original, and ornamental Design for Puppet, of which the following is a specification, reference being had to the accompanying drawing, forming part thereof.

In the drawings:

I claim:

A new and ornamental design for a puppet, as shown.
